FUEL BURNER

Ervin G. Bailey, Easton, Pa., assignor to Fuller
Lehigh Company, Fullerton, Pa., a corporation
of Delaware

Application July 30, 1930, Serial No. 471,674

2 Claims. (Cl. 110—28)

This invention relates to fuel burners that are especially useful for burning powdered fuel such as coal, but it is not restricted to this particular use.

5 A plurality of burners may be used and each one is provided with a narrow exit into the furnace to project the fuel in a thin sheet and is located so that the plane of the burner exit is at an angle to the horizontal. The burners can be 10 applied to a furnace having water cooling tubes in the walls thereof, and extends across a plurality of tubes.

The invention will be understood from the description in connection with the accompanying 15 drawings in which Fig. 1 is a vertical section through the furnace showing an illustrative embodiment of the invention; Fig. 2 is a vertical section along the line 2—2 of Fig. 1; Fig. 3 is a horizontal section along the line 3—3 of Fig. 1; Fig. 4 is in part a side elevation and in part a 20 vertical section along the line 4—4 of Fig. 3 and Fig. 5 is a vertical section on an enlarged scale through one of the burners and the adjacent wall of the furnace.

25 In the drawings reference character 1 indicates a boiler furnace that is provided with water tubes 2 extending upwardly along the walls of the furnace. The lower ends of the tubes 2 are connected to lower horizontal headers 3 and the upper ends 30 of these tubes extend outwardly into horizontally disposed headers 4. The tubes 2 are lined with tile 5, or the well-known Bailey blocks, to form continuous walls. The headers 3 and 4 may be connected by means of re-circulating tubes 6 out- 35 side of the furnace.

The floor 7 of the furnace, that may be made of refractory material, is supported upon the cross supports 8 and molten slag from the products of combustion may collect upon the floor 7, 40 as indicated at 9, and is drawn out through the slag tap opening 10 at intervals. The walls of the furnace thus extend upwardly from the floor 7.

A water tube boiler may be located above the 45 furnace 1, only the lower row 11 of the inclined bank of tubes of the boiler being indicated on Fig. 1 of the drawings. The headers 3 and 4 may be connected to the water circulation system of the boiler in the usual way.

50 A plurality of fuel burners 15 is provided along one wall of the furnace and a plurality of fuel burners 16 is provided along the opposite wall of the furnace to project fuel and primary air into the furnace, the secondary air being furnished through the secondary air boxes 17,

through which the fuel burners 15 and 16 extend.

The fuel burners 15 and 16 are alike and one of them is shown in section on an enlarged scale in Fig. 5 and will now be described.

The ordinary tile or blocks 5 that line the tubes 2 of the furnace are removed at the places where the burners 15 and 16 are installed. Special tile or blocks 5' are installed in these places leaving inclined openings for the burners. Each fuel burner comprises a fan-shaped conduit, or inlet, 18 that widens out toward the exit end so that the mouth, or exit thereof, terminates in the equivalent of a narrow slit 19. A row of blocks 20 have their sides that are toward the exit 19 V-shaped so that the stream of air and fuel will 25 be divided by this row of blocks into two diverging sheets. The blocks of refractory material 20 are kept in place on the tubes 2 by means of the U-bolts 21. They extend approximately along the middle line of the inclined opening between 30 the rows of special tile or blocks 5'.

The spaces 22 between the tubes 2, above and below the mouth 19 of the burner, may be regulated by means of the dampers 23 that are operated by the levers 24. An ignitor 25 for the fuel 35 extends through the air box 17 and terminates near the end of the burner.

The burners 15 on one side of the furnace are mounted with their narrow exit ends inclined to the horizontal, or at an angle to the lateral 40 extent of the wall each one extending across several tubes in the furnace wall, all the burners on one wall having their exits parallel, as most clearly indicated in Fig. 2. Thus each burner projects through a wall at an angle to the plane 45 of the floor, and, as will be seen in Fig. 5, the longitudinal axis of the burner also lies at an angle to the plane of the wall and the plane of the floor. Corresponding burners are provided along the 50 opposite wall of the furnace with their exits inclined in the opposite direction. By inclining the burners, as described, they can be located at substantially the same elevation and a larger area of burner port openings and air port openings can be provided in a given horizontal distance 55 than would be possible if the burners have their 60 openings horizontal and at the same level. By this arrangement the burners do not overlap and all of them can be placed at the same distance 65 from the refractory floor of the furnace. Also 70 by having the burners in opposite walls and inclined in opposite directions, that is to say, each burner projecting through a wall at an angle to a burner in the opposite wall, an excellent interference of flame and gases is provided inside the 75

80 furnace. The fuel burners 15 and 16 are inclined 85 so that the fuel is projected in a thin sheet and the primary air is directed against the fuel sheet to 90 produce a flame that is directed against the water tubes 2. The fuel is projected in a thin sheet so that the flame is relatively small and the heat is concentrated 95 on the water tubes 2. The fuel is projected in a thin sheet so that the flame is relatively small and the heat is concentrated 100 on the water tubes 2. The fuel is projected in a thin sheet so that the flame is relatively small and the heat is concentrated 105 on the water tubes 2. The fuel is projected in a thin sheet so that the flame is relatively small and the heat is concentrated 110 on the water tubes 2.

furnace where they impinge against each other, thus causing better mixing and turbulence of the fuel and air and giving better combustion efficiency. It will be realized that the elongated opening of each burner lies at an angle to the elongated opening of a burner in the opposite wall, thus producing the effects which have just been described.

I claim:

10 1. In a furnace having a substantially vertical side wall, a pair of separate closely spaced elongated fuel burner ports formed in said wall, each of said ports being arranged with its longitudinal center line forming an oblique angle with the horizontal and corresponding portions of said

ports being arranged at similar elevations in said wall, and means for discharging substantially parallel elongated streams of fuel through said ports.

15 2. In a furnace having a pair of opposite vertical walls, an elongated fuel burner port formed in each of said walls having its longitudinal center line forming an oblique angle with the horizontal, the ports in said opposite walls being oppositely inclined and having their centers located at substantially similar points in said walls, and means for discharging elongated streams of fuel through said ports toward and impinging on one another in said furnace.
